[57] ABSTRACT

An organic dyeing liquor, circulating hot through a vat filled with textiles to be dyed, is passed in a terminal stage through a cooler in cascade with a filter. As the temperature of the solvent progressively decreases, dyestuff is precipitated in the filter which is positioned close to the cooler, preferably in a common housing. Upon final rinsing with the substantially dyestuff-free solvent, impregnants or other treatment agents may be admixed therewith.

SYSTEM FOR DYEING TEXTILES AND THE LIKE

Our present invention relates to a system for dyeing a load of textile materials or the like with the aid of a treatment liquor consisting essentially of an organic solvent, e.g., perchloroethylene or a similar halogen-substituted hydrocarbon, having a dyestuff dissolved therein.

Upon completion of the dyeing step proper, i.e., after the load has been substantially saturated with dye extracted from the solvent, a certain amount of the hot solution generally remains in the dyeing vessel which may be a vat or a rotating drum. A simple draining of this residual volume is often inadmissible since the goods, particularly if they are in motion, would tend to develop objectionable creases and wrinkles. If, on the other hand, the liquor is allowed to cool in the vessel before being discharged therefrom, some of the dyestuff remaining in solution may precipitate onto the goods and impair their colorfastness; thus, upon the subsequent evaporation of the remaining traces of solvent, the color is likely to rub off onto adjoining objects. It has therefore been hitherto necessary to rinse the goods rather vigorously, usually several times, with pure solvent. In order to prevent the aforescribed precipitation of residual dyestuff on the goods, the rinsing fluid had to be preheated to a temperature level close to that of the dyeing solution, with progressively lower temperatures used during the successive rinsing steps.

The general object of our invention is to provide an improved process and apparatus for dyeing textiles or similar goods in organic solutions with avoidance of the aforesaid drawbacks.

More particularly, our invention aims at reducing the energy input and increasing the rate of solvent recovery in a system of this type.

These objects are realized, pursuant to the present invention, by recirculating the spent dyeing liquor in a closed path through the treatment vessel by way of a cooler and a filter, the latter removing the residual dyestuff precipitated from the solution as the temperature drops. The circulated solvent, depleted of dyestuff, displaces the original concentrate in the vessel and also entrains any particles of colorant that may have begun to settle on the goods.

If this recirculation process is carried to completion, i.e., to a point where the solvent is at a temperature low enough to let it give off practically all its solute, the substantially pure solvent may be used for the final rinse. The purified solvent, which no longer passes through the filter, may also be used as a vehicle for some other finishing agent with which the goods are to be treated.

Suitable dyestuffs, soluble in nonpolar organic solvents such as perchloroethylene, trichloroethylene and carbon tetrachloride, include nitro, azo and anthraquinone compounds.

In order to avoid contamination of the conduits by precipitating dyestuffs, the connection between the cooling stage and the filter stage should be as short as possible. In a particularly advantageous embodiment, we dispose both stages in a common housing so that the fluid leaving the cooler is immediately intercepted by the filtering mass. This mass may be admixed in comminuted form with the fluid stream ahead of the filter elements which are preferably in the form of perforated

tubes whose surface becomes coated with the mass. Included in this mass may be an adsorbent, such as activated charcoal or fuller's earth, having a high affinity for the precipitate.

5 The invention will be described in greater detail hereinafter with reference to the accompanying drawing in which:

FIG. 1 is a block diagram of a system embodying our present improvement; and

10 FIG. 2 is an elevational view, partly in section, of a combined cooling and filtering stage included in the system of FIG. 1.

The system in FIG. 1 comprises a treatment vessel 1, such as a drum rotatable about a vertical axis, which is 15 provided at the top with a loading aperture 3 and is supplied with treatment fluid through an incoming conduit 5 entering near its top, the fluid exiting at the bottom of the vessel via an outgoing conduit 4. It will be understood that these conduits may terminate at a stationary 20 shell in which the perforated drum proper is journaled.

Conduits 4 and 5, which are provided with respective shutoff valves 8 and 7, form part of a closed path which includes a pump 6, a needle trap 12 and further valves 9 and 26. Pump 6 is shown provided with a separate entrance port 6' by which an adjuvant, such as the aforesaid finishing agents, may be admixed with the fluid stream.

A branch of this path, bypassing the valve 26, includes a cooler 13 and a filter 2 in cascade, this branch 30 being controlled by a pair of valves 10 and 11. Other branch lines lead from the high-pressure side of the pump 6, via a valve 18, to a solvent reservoir 19 and from that reservoir, via a valve 25, to the low-pressure side of the pump. Reservoir 19 forms part of a separate 35 circuit 23 which includes valves 16 and 24, a still 17, a condenser 21 and a water separator 22. Filter 2 has a drain emptying through a valve 20 into still 17.

Cooler 13 is a heat exchanger through which a cooling fluid is circulated via pipes 14 under the control of 40 a valve 15.

In operation, concentrated dyeing solution heated in reservoir 19 is delivered to vessel 1 via open valves 25, 26 and 7 by pump 6, the other valves being closed at 45 this time. When the vessel has been filled and the load is soaked, the solution can be recirculated by way of conduits 4 and 5, valves 7, 8, 9 and 26 being open at this stage. Further heating means, not shown, may be included in this path to maintain the liquor at the desired elevated temperature.

50 Upon termination of the dyeing process proper, valve 26 is closed whereas valves 10 and 11 are opened to let the solution circulate through cooling stage 13 and filter stage 2. The progressive decrease of the fluid temperature causes the precipitation of residual dyestuff in the filter 2 which may contain a mechanically acting microporous layer, e.g., of silica, admixed with an adsorbent such as activated charcoal. Next, the more or less depleted solution is deviated from the cooler 13

55 and filter 2 to the still 17 by closing the valves 10 and 26 while opening the valve 16, the vapors being reliquefied in condenser 21 and returned to the reservoir 19 via valve 24 and water separator 22. If the circulating solvent has been sufficiently purified, it may also be returned directly to the reservoir from the discharge side of pump 6 through valve 18. Solids remaining 60 in the filter 2 are discharged by way of valve 20 to the still 17.

FIG. 2 shows a preferred construction of the filter stage 2 which in this instance incorporates the heat exchanger schematically indicated at 13 in FIG. 1. This device comprises a generally cylindrical housing 27 formed at the top with a manifold 27' which opens into conduit 5. Conduit 4, carrying the solution discharged from vessel 1, communicates with a T-shaped pipe 29 inside the housing, this pipe passing through a centrally disposed heat exchanger 30 and opening into the housing at opposite ends 33 and 34. A peripheral array of filter elements 28 (only two shown) surrounds the tubular heat exchanger 30, each of these elements comprising a perforated tube 36 whose peripheral surface is coated with a permeable deposit 35 of filter particles as described above. The layer 35 may be dislodged, after termination of normal operation, by the admission of high-pressure fluid into manifold 27' through conduit 5, the tubes 28 communicating with this manifold at the top while opening into the main housing chamber at the bottom. Coolant is circulated through the heat exchanger 30 via a pair of pipes 31 and 32.

As will be apparent, the filter elements 28 are disposed downstream of the cooler 30 within housing 27, with reference to the direction of solvent flow indicated by arrows in FIG. 2; this corresponds to the relative positioning of the cooler 10 and the filter 2 in FIG. 1.

The filter 2 could, of course, also be used to extract other entrained matter from the fluid stream.

Before switching to the still 17, the pure solvent may be recirculated one or more times through the closed path used for the initial dyeing step, by way of valve 26 and with valves 10 and 11 closed. It is at this stage that an impregnant or other treatment agent may be introduced into the flow at port 6' to impart a desired finish to the goods in vessel 1.

We claim:

1. A system for dyeing a load of textile materials or the like, comprising:
a dyeing vessel adapted to receive a load to be dyed; a supply of hot dyeing liquor consisting essentially of 40 an organic solvent with a dyestuff dissolved therein; conduit means for delivering said liquor to said vessel and for establishing a closed path for the circulation of the liquor through said vessel; cooling means for said liquor in said path; downstream 45 filter means for residual dyestuff inserted in said path downstream of said cooling means, said cooling

means being operative to lower the temperature of said liquor to a level facilitating the precipitation of said residual dyestuff in said filter means; and pump means in said path for successively driving said liquor through said cooling means and said filter means before returning same to said vessel.

2. A system as defined in claim 1 wherein said cooling means immediately precedes said filter means.

3. A system as defined in claim 2, further comprising 10 a common housing for said cooling means and said filter means, said housing having an inlet for said liquor connected to said cooling means and an outlet for said liquor connected to said filter means.

4. A system as defined in claim 3 wherein said cooling means comprises a heat exchanger disposed centrally in said housing, said filter means comprising an array of tubular filter elements surrounding said heat exchanger and opening into said housing, the latter being provided with a manifold connecting said elements to said outlet.

5. A system as defined in claim 1 wherein said supply includes a solvent reservoir, a still and a condenser forming part of a closed circuit bypassing said cooling means and said filter means, the latter being provided with a drain connectable to said still.

6. A system as defined in claim 1 wherein said pump means is provided with an entrance port for the admixture of a treatment agent with the circulating solvent.

7. A system for dyeing a load of textile materials or the like, comprising:

a dyeing vessel adapted to receive a load to be dyed; a supply of hot dyeing liquor consisting essentially of an organic solvent with a dyestuff dissolved therein; conduit means for delivering said liquor to said vessel and for establishing a closed path for the circulation of the liquor through said vessel; cooling means for said liquor in said path; filter means for residual dyestuff inserted in said path downstream of said cooling means; and pump means in said path for successively driving said liquor through said cooling means and said filter means before returning same to said vessel; said supply including a solvent reservoir, a still and a condenser forming part of a closed circuit bypassing said cooling means and said filter means, the latter being provided with a drain connectable to said still.
